CLAIM

The ornamental design for a battery, as shown and described.

DESCRIPTION

FIG. 1 is a top, rear, right perspective view of the claimed design for a battery;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The dot-dash broken lines depict the boundaries of the claim and from no part thereof. The evenly spaced broken lines depict portions of the battery that form no part of the claimed design.
